UNITED STATES PATENT OFFICE.

FERDINAND PHILIPS, OF PHILADELPHIA, PENNSYLVANIA.

MACHINE FOR DRAWING WIRE.

SPECIFICATION forming part of Letters Patent No. 651,051, dated June 5, 1900.

Application filed June 3, 1898. Serial No. 682,433. (No model.)

To all whom it may concern:

Be it known that I, FERDINAND PHILIPS, a subject of the Emperor of Germany, residing in the city and county of Philadelphia, in the 5 State of Pennsylvania, have invented a new and useful Improvement in Machines for Drawing Wire, of which the following is a true and exact description, reference being had to the accompanying drawings, which 10 form a part thereof.

My invention relates to the construction of a machine for drawing wire, and has for its object to simplify and improve the construction of such machinery, and particularly to 15 provide machinery for drawing the wire which will act with greater smoothness and evenness than has heretofore been the case, and thus lessen the tendency to break the wire in the act of drawing it.

20 The nature of my improvements will be best understood as described in connection with the drawings, in which they are illustrated, and in which—

Figure 1 is a plan view of a wire-drawing machine embodying my improvements. Fig. 2 is a cross-sectional elevation taken as on the line 1 1 of Fig. 1. Fig. 3 is a horizontal section taken as on the line 2 2 of Fig. 2 looking upward. Fig. 4 is a sectional elevation 30 taken as on the line 3 3 of Fig. 1. Fig. 5 is a section through the "block" or drum, taken on the line 4 4 of Fig. 1. Fig. 6 is a section through the die and die-holder, taken as on the line 5 5 of Fig. 1; and Fig. 7 is a plan view 35 of the drawing-in tongs and attached chain.

A indicates the framing of the machine, which may be of any convenient construction.

B B are the bearings for the power driving-shaft C, D indicating a pulley on said shaft 40 by which it is driven.

B' is a step-bearing for the vertical shaft H, B² indicating a further bearing supported on the upper part of the frame for this shaft.

E is a sleeve secured, as by means of a 45 spline and feather, (indicated at e,) to the shaft C, so as to rotate with said shaft. Extending out from the end of this sleeve is the disk E', having a rim E², over which fits a flange of an annular disk E³, which by means 50 of a series of bolts E⁴, passing through the disk E', is connected with a series of bent levers E⁵, the outer ends of which rest against

the rim E², while their other arms are connected by links E⁶ with a sleeve E⁷, in the outer end of which is formed an annular 55 groove E⁸, into which extends pins E⁹, attached to the arms of a forked lever E¹⁰, connected in turn to a rock-shaft E¹¹, to the end of which the clutch-actuating lever E¹², Fig. 2, is attached. Situated between the annular plate E³ and the disk E' is the annular block-face F, attached to one end of a sleeve F', supported upon the shaft C and connected by bolts or otherwise, as indicated, with a sleeve F², upon the end of which is formed 65 or secured a miter-wheel F³.

The device as described is simply a friction-clutch, by means of which the sleeves F' and F², connected with the connected miter-wheel F³, can be at will either clamped to the shaft 70 C so as to rotate with it or permitted to remain stationary while the shaft C is in motion, and the particular design of the clutch is not material to my invention, as any equivalent form of friction-clutch may be used with 75 substantially the same effect.

The miter-wheel F³ is in permanent engagement with a miter-wheel G, having, as shown, a pitch-line circumference six times that of bevel gear-wheel F³ and which should always 80 be of very considerably larger dimensions than F³. Said wheel G in turn is secured to the vertical counter-shaft H, the lower end H' of which is stepped in the bearing B' and which, as shown, has a partially-squared portion H² near its top and the cylindrical top portion H³ above said squared portion. Centered on the portion H³ of the vertical shaft is the head I⁴ of the block or drum I, said drum being provided with an upwardly-extending flange I' and formed or provided on its under side with recesses I⁵, (see Figs. 1 and 3,) which recesses in the normal position of the block engage the fingers or arms of the drum-rotating device, (indicated at J,) which 90 is secured on the squared portion H² of the shaft, so that in normal position of the parts the drum or block revolves with the vertical shaft; but by raising the drum slightly, so as to disengage the recess I⁵ and the device J, 95 the drum may remain stationary without being entirely withdrawn from the shaft.

At I², Fig. 2, I have indicated a hole or perforation in the lower portion of the drum of

a shape suitable to be entered and engaged by the hook P^2 , attached to the joint P' , which in turn is connected with the drawing-in tongs P .

5 At K , I have indicated a vise or gripping device such as is commonly employed with wire-drawing blocks and by which the end of the wire is clamped to the block or drum after it has been drawn through the die to a 10 sufficient distance.

To a bracket (shown at A') I have indicated as secured by means of a pivot-pin M the die-holding plate L , having upwardly-extending arms L' , between which is placed the 15 die O , having a number of wire-drawing apertures formed in it and which is clamped in desired position by means of the screw N , working through a cross-bar L^2 , connected with the tops of the arms L' .

20 At Q (see Figs. 2 and 4) I have indicated a brake arranged to act upon the under side of the flange I' of the drum or block and connected with a rod or rods Q' , working in a bearing B^3 , said rod and brake being raised 25 into contact with the drum when desired through the pivot-lever Q^2 , actuated, by means of a link or connection Q^3 , by the foot-treadle Q^4 .

In operating my machine the pointed end of 30 the wire to be drawn is inserted through one of the perforations in the die O and gripped by means of the drawing-in tongs P , the hook P^2 attached to which tongs is secured to the periphery of the drum I , as by inserting it in 35 the perforation I^2 . The operator then by means of the clutch-lever E^{12} actuates the friction-clutch, engaging the sleeves F' and F^2 with a constantly-revolving shaft C , so as to cause the gear-wheel F^3 to rotate with the 40 shaft and to rotate the vertical shaft and the drum or block attached to it, and by this means the wire is drawn through the die to any desired distance and by an even constantly-applied force and, moreover, one 45 which by a proper manipulation of the clutch can be brought into operation as gradually as may be desired, thus avoiding all the sudden shocks incident to wire-drawing machinery as heretofore constructed and the consequent 50 very frequent breaking of the wire in the act of drawing in. After a sufficient amount of the wire has been drawn through the block the drawing-tongs are disconnected from the wire and from the drum and the end of the 55 wire clamped to the drum or block by means of the vise K , the machine of course being stopped while this adjustment is made and then started again by means of the friction-clutch without sudden jar or shock, and it will 60 readily be understood that by means of the brake Q the operator has it in his power to check the momentum of the block and connected parts with any desired degree of rapidity after the positive connection with the 65 driven shaft has been severed by releasing the clutch.

It is of the essence of my invention that the

intermediate gearing, as shown, consisting of the gears F^3 and G and the friction-clutch connecting gear F^3 with the driving-shaft, should 70 be of a character which in transmitting the motion of the driving-shaft to the drum will naturally reduce speed and increase power and that the friction-clutch member of such 75 gearing should always be applied to a relatively high speed member of the gear mechanism. The importance of this construction lies in the fact that it relieves the friction-clutch of the duty of directly withstanding the 80 full power exerted by the drum or block and in the construction shown imposes on it only one-sixth of this duty, a duty well within the capacity of such clutches, while the full power exerted by the drum has been found to be too 85 great for such clutches as they are now generally constructed and as it is convenient to construct them.

Having now described my invention, what I claim as new, and desire to secure by Letters Patent, is—

1. In a machine for drawing wire, the combination with a die of a drawing drum or "block," a drum-driving shaft, speed-reducing and power-increasing intermediate positive gearing for coupling the shaft with the 95 drum and a friction-clutch interposed in said mechanism and acting on a high-speed member thereof.

2. In a machine for drawing wire, the combination with a die of a vertical drawing and winding drum or "block," a drum-driving shaft, speed-reducing and power-increasing intermediate positive gearing for coupling the shaft with the drum and a friction-clutch interposed in said mechanism and acting on 105 a high-speed member thereof.

3. In a machine for drawing wire, the combination with a die of a drawing drum or "block," a drum-driving shaft, speed-reducing and power-increasing intermediate positive gearing for coupling the shaft with the 110 drum, a friction-clutch interposed in said mechanism and acting on a high-speed member, pulling-in tongs having a chain connection and means for engaging said chain with 115 the periphery of the drum.

4. In a machine for drawing wire, the combination with a die of an upright wire-drawing drum or "block" arranged as described to draw the wire through the die, a vertical 120 shaft supporting said block, a bevel-wheel G secured to the vertical shaft, a bevel-wheel F^3 of much smaller diameter secured to a sleeve mounted on the horizontal shaft and in engagement with wheel G , and a friction-clutch arranged to connect and disconnect the sleeve carrying the gear-wheel F^3 with the horizontal shaft.

5. In a machine for drawing wire, the combination with a die of a vertical drawing and winding drum or "block," a drum-driving shaft, speed-reducing and power-increasing intermediate positive gearing for coupling the shaft with the drum, a friction-clutch in-

terposed in said mechanism and acting on a high-speed member thereof and a brake arranged to act directly on the drum.

6. In a machine for drawing wire, the combination with a die of an upright wire-drawing drum or "block" arranged as described to draw the wire through the die without the intervention of intermediate drums or spools, said "block" having a hub I^4 to fit over but not directly engage the upper end of a vertical shaft and a recess, as I^3 , formed in the under side of its hub, a vertical shaft sup-

porting said block, a block-engaging device, as J, secured to the vertical shaft so as to turn with it and adapted to engage the recess I^3 in the block-hub when the block is in normal operative position and means, including a friction-clutch for imparting motion to the vertical shaft and through it to the block. 15
